UNITED STATES PATENT OFFICE

DANIEL T. MACLEOD, OF MILWAUKEE, WISCONSIN, ASSIGNOR TO PERFEX CORPORATION, OF MILWAUKEE, WISCONSIN, A CORPORATION OF WISCONSIN

COOLING RADIATOR FOR INTERNAL COMBUSTION ENGINES

Application filed July 7, 1928. Serial No. 291,086.

This invention relates to cooling systems, particularly designed for use in railway cars driven by power derived from Diesel or other internal combustion engines either directly or 5 through electrical equipment.

An object of the invention is to provide an improved cooling system located above the motor, preferably on the roof of the car in order to avoid the objectionable obstruction 10 to vision caused by the radiator in its usual location at the front of the cab. A further object of the invention is to so arrange the radiator in multiple units in an arrangement which will economize headroom but insure 15 that each section may be cooled by air that is not successively passed through the different sections of the radiator. Another object of the invention is to provide for the automatic circulation of air through the radiator under 20 certain conditions of operation, as by forward movement of the car, and for forced circulation under other conditions.

These objects are accomplished by a construction as shown in the drawings in which: 25 Figure 1 is a longitudinal sectional view of a radiator compartment on the roof of a car showing the several sections of the radiator arranged therein.

Fig. 2 is a fragmentary perspective view of 30 the upper front part of the car equipped with the improved cooling system.

Fig. 3 is a transverse sectional detail taken on the line 3—3 of Fig. 1.

By means of the present arrangement of 35 cooling system, the car containing an internal combustion engine power unit has at the roof a space which is utilized for housing the cooling radiator for the engine. This radiator is thus located in order to allow more room 40 around the power unit and reduce the obstruction to vision and also to make use of the strong drafts of air which are generated at the roof of the car by its own movement and resultant windage. Means are also pro- 45 vided for forcing a draft through the cooling unit when the car is operated slowly or backwardly. This forced draft means is set into operation by or coincidentally with the movement of a gate to position for changing the 50 normal flow of air through the radiator.

Referring to the drawings, the roof 1 of car 2 supports a radiator compartment 3 formed by the side walls 4 connected by the angle irons 5 and the transverse louvers 6 at the top thereof. A gate 7 is hinged at 8 to 55 the lower front end of compartment 3 and controls the inlet 9 for air when the car is traveling in a forward direction. There is an outlet 10 for air when a fan 11 is made use of for drawing air through the compartment 60 3 in a reverse direction, as when the car is traveling backwardly, or standing still with the engine running. The fan 11 is driven by a motor 12 in a circuit under the control of switch 13 which operates with the gate 7. 65 The latter carries an arm 14 to which is connected a rod 15 leading down into the cab of the car. The gate 7 is set in the desired position manually by means of rod 15. When it is in position to close the air inlet 9, 70 the switch 13 is closed and a fan 11 then draws the air through compartment 3 between the louvers 6 and through the opening 16 at the rear of the radiator compartment. When the fan is in operation, the air is dis- 75 charged through the outlet 17.

The radiator sections 18 are arranged one in front of the other in compartment 3 but are set obliquely so as only to require a compartment of minimum height and so as 80 to have a convenient arrangement where the air passing through the compartment is divided between the different sections of the radiator. Each section of the radiator rests upon L-shaped supports made of angle irons 85 19 secured to the inner sides of walls 4. Transverse partitions 20 between the walls 4 prevent the air from passing between or around the radiator sections. The construction of the radiator may be of the types used 90 for engine cooling purposes, the form illustrated in Fig. 3, comprising the header compartments 21 connected by the tubes 22. Conduits 23 lead from the headers 21 to the water jacket of the motor not shown. 95

In the operation of the cooling system, assuming that the car is traveling in a forward direction and the gate 7 is down, air enters the compartment 3 in the direction indicated by arrow 24. The draft produced by the 100

forward motion of the air causes it to pass through the radiator sections and out through the opening 16 and spaces between the louvers 6. These louvers also protect the radiator from the sun. If the car is stopped or driven in a reverse direction, rod 15 is thrust upwardly by the operator raising and closing gate 7 and at the same time closing the switch 13 for motor 12. The fan 10 then draws the air through the radiator sections in a reverse direction, the air entering the compartment 3 between the louvers and through the opening 16 and being discharged at the outlet 17.

15 The effect of the fan is augmented by the relatively weak natural draft induced by the movement of the car. Even without the fan, and with gate 7 lowered, there would be a substantial draft induced through the opening 16 toward the front and out of the opening 9, when the car travels backwardly; but ordinarily such a draft alone would be inadequate.

Although but one specific embodiment of 25 this invention has been herein shown and described, it will be understood that details of the construction shown may be altered or omitted without departing from the spirit of this invention as defined by the following 30 claims.

I claim:

1. In a cooling system of the class described for a railway car, means providing a compartment at the upper part of one end 35 of the car, a plurality of obliquely arranged radiator sections in said compartment, and means for preventing air from passing through one to another of said radiator sections.

40 2. In a cooling system of the class described for a railway car, means providing a compartment at the upper part of one end of the car, a plurality of obliquely arranged radiator sections in said compartment, and 45 partitions connecting the top of one of said radiator sections to the bottom of the next for preventing air from passing through one to another of said radiator sections.

3. In a cooling system for the power plant 50 of a railway car, means providing a compartment at the upper part of one end of the car, a plurality of obliquely arranged radiator sections in said compartment, openings in said compartment for the intake and discharge of air caused to flow by the forward 55 movement of the car, a fan for causing the air to flow through said compartment, a gate for closing one of said openings, and means coordinated with the operation of said fan 60 for controlling said gate.

4. In a cooling system for the power plant of a railway car, means providing a compartment at the upper part of one end of the car, a plurality of obliquely arranged radiator 65 sections in said compartment, openings

in said compartment for the intake and discharge of air caused to flow by the forward movement of the car, an electric fan for causing the air to flow through said compartment, a gate for closing one of said openings, an operating member for said gate, and a switch controlled by said operating member for controlling said fan. 70

5. In a cooling system of the class described for railway cars, means providing a compartment at the upper part of the car having an air inlet, a plurality of radiators mounted in said compartment one behind another in overlapping stepped arrangement, and means for preventing air from flowing through one to another of said radiators. 75

6. In a cooling system of the class described for a railway car, a housing structure at the upper part of one end of the car and having openings at its ends and at its top, a plurality of radiator sections arranged in said housing and means cooperating with said radiator sections to constrain them to parallel draft operation under the influence 80 of the travel windage of the car. 90

7. In a cooling system of the claims described for a railway car, a housing structure at the upper part of one end of the car, said housing structure being arranged fore and aft of the car and having its forward end provided with an air inlet opening and having its top portion and rearward end formed with air outlet openings, there being an auxiliary outlet opening communicable with the forward end of the housing, closure means for shutting off the auxiliary outlet opening or the inlet opening at the forward end of the housing, a plurality of radiator sections arranged in the housing and constrained to parallel draft operation whereby the radiator sections are adapted to be cooled under the influence of the travel windage of the car when the car is moving forwardly, and a motor operated fan for reversing the direction of the air flow through the housing to cool said radiator section when the car is standing still and also to augment the influence of the travel windage when the car is traveling backwardly. 100

8. In a cooling system of the claims described for a railway car, a housing structure at the upper part of one end of the car and having openings at its ends and at its top whereby the travel windage of the car sets up a flow of air through the housing, a plurality of radiator sections in inclined position in the housing, means constraining said radiator sections to parallel draft operation, and a plurality of louvers in the opening at the top of the housing structure to protect the radiator sections from the sun. 110

9. In a cooling system of the class described for a railway car, a longitudinal series of radiator sections constrained to par- 115

allel draft operation, a housing formed and adapted to utilize the travel windage of the car, when the car is running forwardly, to set up a flow of air through the housing for cooling said sections, and means for reversing the direction of flow through the housing to augment the action of the travel windage when the car is moving backwardly and to provide for the cooling of the radiator sections when the car is standing still.

10 Signed at Chicago, Illinois, this 5th day of July, 1928.

DANIEL T. MACLEOD.
